UNITED STATES PATENT OFFICE.

SAMUEL CLELAND DAVIDSON, OF BELFAST, IRELAND.

VENTILATION OF TUNNELS.

No. 869,297.

Specification of Letters Patent.

Patented Oct. 29, 1907.

Application filed January 27, 1904. Serial No. 190,787.

To all whom it may concern:

Be it known that I, SAMUEL CLELAND DAVIDSON, a subject of the King of Great Britain and Ireland, residing in Belfast, Ireland, merchant, have invented 5 certain new and useful Improvements in the Ventilation of Tunnels, of which the following is a specification.

My improvements relate more particularly to railway tunnels, but are applicable also to mines, large 10 main sewers, or any tubular conduits or passages which are freely open to the atmosphere at both ends (hereinafter referred to as tunnels).

In railway tunnels a clear passage way for the train must always be kept freely open, throughout the entire length as also at each end of the tunnels, and when 15 said tunnels pass through mountains or under rivers, or under cities where it is impracticable to have any or sufficiently large or numerous vertical shafts or flumes therefrom to insure sufficient ventilation the air within said tunnels must in some cases be put into motion so that a through current is established from one end to the other whereby a flow of fresh air will enter 20 the tunnel at one end and the exhaust air flow out at the opposite end, with sufficient velocity to maintain a certain standard of purity in the air within the tunnel. 25 In such instances the methods hitherto generally preferred for setting up this necessary air current through the tunnels consists of various forms of air injecting apparatus at one end of the tunnel, in one of which for

example an arch-like belt or film of air is driven into the tunnel at a high velocity along the vertical sides and arched top of the tunnel portal, which must necessarily be bell-mouthed to a sufficient enlargement to provide for the arch-like casing or chamber from 30 which said air belt issues and at same time leave a clear space within said arch-like casing of corresponding size with the passage way for the trains through the tunnel itself. The air from said air belt on being injected into the tunnel at a high velocity creates also an induced flow of air through the train passage way within 35 the arch of the air belt casing which mixes with the air from the belt, and the mixture then flows through and out from the opposite end of the tunnel, but at a much slower velocity than that of the relatively smaller

40 volume of air issuing from the belt. It is however well known that the power required to move a given volume of air increases in the ratio of the square of the velocity of air from the belt which volume is usually about one half to two-thirds of the total volume 45 of the air in motion through the tunnel, these proportions having been indicated in some practical tests which have been made in tunnels ventilated in this way, and it has also been indicated that the injected air from the belt requires to have a velocity of injection equal 50 to about 6,000 lineal feet per minute to produce a flow through the body of the tunnel of about one quarter

of the initial velocity of the air belt injection, or only about 1500 lineal feet per minute, as much of the force of the injected air, while at its highest velocity, is wasted by impact and friction against the bell-mouthed 60 sides of the tunnel portal. It is obvious therefore that to impart a velocity of 6,000 feet per minute to say one half of the total volume of air passing through the tunnel, will require 16 times more power than same volume would absorb if moved at one-fourth of that velocity, 65 and 8 times more power than it would take to move double that volume or say the whole volume passing through the tunnel if it were practicable to impart direct impulsion to same. Hence an important saving in power would be effected if instead of applying 70 the high initial velocity of say 6,000 lineal feet per minute to say one half of the total air current moving through the tunnel to produce a movement in same of only 1500 feet per minute, this same movement could be effected by having the initial impulsion velocity of 75 the whole of the air current through the tunnel more nearly approaching that of its average rate of flow through same.

It is the object of my invention to produce a sufficient air current through said tunnels to maintain the required purity of the air within same with an important saving in power and at the same time avoid using the cumbersome appliances necessary for the injection systems as hitherto employed at the portals of the tunnel. 85

According to my invention I produce an air current through tunnels by means of a fan or fans so arranged and located within the tunnel as not to interfere with any required freedom of passage therethrough and so that air is drawn directly from the tunnel into said fan 90 or fans and discharged therefrom in a direction which is either parallel with or at a slight angle to the axis or line of the tunnel, whereby a general flow of the air contents of said tunnel is produced in the direction of the air discharge from said fan or fans. Fans acting as 95 described may be arranged at intervals so as to act as relays one to the other whereby tunnels of any length can be efficiently ventilated with a minimum cost of apparatus and at a minimum requirement for power.

In applying my invention in one form to a comparatively short tunnel of, for example say 300 yards in length, I construct a recess in the side of the tunnel (similar to the shelter recesses ordinarily provided for workers in tunnels) at about 100 yards from the end of the tunnel at which the fresh air is to be drawn into 100 it, and of sufficient height, width and depth back from the line of the tunnel side, as to give ample room for placing a fan therein, with driving motor attached to it, and space to get around it conveniently on all sides. The type of fan which I preferably employ is that described in the specification of Letters Patent granted 105 to me and dated 27th, November 1900, but any other

kind of fan may be used. Said fan being thus located to one side of the line of the tunnel forms no obstruction to the passage of trains through same and its inlet opening is so arranged as to draw its air supply from the 5 tunnel, and its discharge is so directed as to inject this air back into the tunnel either parallel with the axis thereof, or at as slight an angle therewith as is practicable in the direction that the air current is to flow through the tunnel. The result of this arrangement is 10 that the suction into the fan and the discharge therefrom act in unison towards setting up a flow through the tunnel, the suction helping to draw the fresh air in from the inlet portal of the tunnel up to the fan, and the discharge from the fan acting as an injector 15 to propel the air in the tunnel from the fan towards the exhaust portal, so that both inlet and discharge of the fan have a combined operative effect towards putting the air within the tunnel into motion, and this double action I have found will produce the same 20 velocity of air flow within the tunnel as would be got by an equal size of fan driving the air at twice the velocity into one end of the tunnel on the air-belt injection system hereinbefore described, and for much less power than required by such air-belt system of injection. 25

According to a further modification of my invention and in order to apply same effectively to long tunnels, of say one or more miles in length, the above described combination of recess and fan within the tunnel is repeated at intervals along the tunnel. The whole 30 length of the tunnel can thus be divided into sections, at the end of each of which a combination of recess and fan operates as a "relay" on the one preceding it, and assuming that the fans are each of the same size, 35 and operating with the same power, then each succeeding "relay" will reinforce the velocity of the air current flowing into, through, and out of the tunnel, with a minimum of loss due to friction by reason of the propelling power being added by a succession of "re- 40 lays" and thereby with a minimum of shock, and as almost any number of fans can thus be employed, to simultaneously operate on the air within the tunnel, it becomes practicable to employ moderate sizes of 45 fans in sufficient number, to total up a united area of inlet thereto, and discharge therefrom, to be equal 50 to the entire cross section of the tunnel, so that the velocity of flow through the fans need only exceed the velocity of flow through the tunnel, by just so much as will replace the loss of velocity due to friction of the 55 main current along the sides of the tunnel, which at the comparatively low velocity usually required (of say about 1500 lineal feet per minute) does not amount to much, when the required impulsion is imparted to the current by "relay", hence by my hereinbefore 60 described invention the required flow of air through the tunnel can be accomplished with a minimum of initial velocity through the fans, and therefore with a minimum of power for driving the fans, which driving power preferably consists of direct coupled electric motors, so 65 controlled from either end of the tunnel, that all the motors and fans can be either started simultaneously, or individually, as required. For instance, when a train is going through the tunnel all the fans could be run at full power simultaneously and maximum ventilation maintained till the train had passed through,

after which the operation of one or more fans at a reduced speed would be sufficient to clear out the remnant of smoke and impurities remaining in the tunnel, and to keep the air in it pure until the next train entered, when full speed and power could again be applied. 70

Reference to the accompanying drawings will more fully explain the nature of my invention and how the same is carried into effect.

Figure 1 is a sectional plan of a short length of tunnel 75 showing the employment therein of a single fan only. Fig. 2 is a cross sectional elevation on line Y-Z of Fig. 1. Fig. 3 is a sectional plan of a tunnel showing two side recesses and fans therein, both acting on the same side of the tunnel, and in the same direction, whereby the second fan acts as a relay to the first fan. It is obvious that a further number of fans may be similarly applied as additional "relays" along the tunnel, according to its length. Fig. 4 is an enlarged sectional plan, showing a side recess in the tunnel, with a fan and its inlet opening 80 located therein and the fan discharge duct carried along the outer side of the tunnel wall and terminating with a cast iron wall box which forms the discharge nozzle from said discharge duct into the tunnel. Fig. 5 is a side elevation looking in the direction of the arrow shown on 85 Fig. 4. Fig. 6 is a sectional plan of tunnel showing the combination of side recesses and fans applied in alternating order on both sides of the tunnel. 90

The letters employed to indicate the various parts are the same in each figure and are as follows:— 95

A A indicates the tunnel. B B the inlet portal of said tunnel. C C the exhaust portal therefrom. D D railway track through the tunnel. E E recesses in the sides of the tunnel. F F fans located within the side recesses E E. G G electric motors direct coupled to fan shaft for driving same. H H the inlet opening or suction eye of fan. J J discharge duct from fan. K K the cast iron wall box forming discharge nozzle from the discharge ducts J J into the tunnel A A. 100

L M is a dotted line indicating the axis of the discharge from the wall boxes K K which discharge forms a slight or acute angle L M N with the axis of the tunnel. 105

Referring to Fig. 1, on the fan being started its operative effects are as follows:—An inflow of air takes place from the tunnel through the entrance to the side recesses (E) into the inlet opening or suction eye (H) to the fan (F) and thence is discharged through duct (J) back into the tunnel (A) along the line (LM) as indicated by arrows, which discharge being in the direction of the tunnel portal (C) impinges into and gradually 110 mixes with the air of the tunnel, and thereby imparts motion to it in the direction of the exhaust portal (C) whereby an induced current into and along the tunnel is created from the inlet portal (B) from which induced current the fan suction draws its supply, and thereby 115 also assists the flow of the air from the inlet portal (B) up to the side recess in which the fan is located. 120

The above is the simple action that takes place in short tunnels where only one fan is employed, as represented in Fig. 1, but where two or more fans are employed, as indicated in Figs. 3 and 6, the second fan, which is further along the tunnel from the inlet portal than the first fan, acts as a "relay" thereto, and its operative effect upon the air within the tunnel being similar 125 it imparts to same an additional impulse towards the 130

portal (C) and the same action takes place with any further number of fans which may be thus employed as "relays" in tunnels of greater length. In Fig. 3, the side recesses and fans are shown as employed on only one side of the tunnel, but when local conditions permit of their being employed on both sides I preferably arrange them in alternating order, as shown in Fig. 6.

What I claim as my invention and desire to secure by Letters Patent is:—

- 10 1. A tunnel having means for moving the column of air contained therein in a direction lengthwise of the tunnel, such means comprising air-forcing means discharging into such column at a point between the ends of the tunnel, said means delivering a blast of air of a cross-section so much smaller than that of said column, that the quantity of air delivered by said blast shall be insufficient to place the sides of said column under any considerable radial pressure, said blast being directed in such manner as to move the latter in the required direction.
- 20 2. A tunnel having means for moving the column of air contained therein in a direction lengthwise of the tunnel, such means comprising a plurality of air-forcing means discharging into such column at different points in the length of the tunnel, said means delivering blasts of air of a cross-section so much smaller than that of said column, that the quantity of air delivered by said blasts shall be insufficient to place the sides of said column under any considerable radial pressure, said blasts being directed in such manner as to move the latter in the required direction.
- 30 3. A tunnel having air-forcing means adapted to draw a portion of the main column of air therefrom, and to discharge it into said column at a point between the ends of the latter in such manner as to move the column in a direction lengthwise of the tunnel.
- 40 4. A tunnel having a plurality of air-forcing means at different points in its length, each of said means adapted to draw a portion of the main column of air therefrom, and to discharge it into said column at points between the ends of the latter in such manner as to move the latter in a direction lengthwise of the tunnel.

5. A tunnel having a plurality of air-forcing means at different points in its length, each of said means adapted to draw a portion of the main column of air therefrom, and to discharge it into said column at points between the ends of the latter in such manner as to move the latter in a direction lengthwise of the tunnel, one of said means being adapted to act upon said column before the effect of the preceding means is exhausted. 45

6. A tunnel having a plurality of centrifugal fans arranged at intervals within the tunnel, each of such fans being adapted to withdraw a portion of the main column of air and discharge it into said column at points between the ends of the latter in the direction in which the column is to be moved, said fans being so arranged so that each fan acts upon the column before the effect of the preceding fan is exhausted, whereby the entire column is maintained in movement. 50

7. A tunnel having means for moving the column of air contained therein in a direction lengthwise of the tunnel, such means comprising a plurality of air-forcing means discharging into such column at different points in the length of the tunnel, said means delivering blasts of air of a cross-section so much smaller than that of said column, that the quantity of air delivered by said blasts shall be insufficient to place the sides of said column under any considerable radial pressure, said blasts being directed in effect into the center of the column, and in a direction substantially parallel therewith. 60

8. A tunnel having a plurality of air-forcing means at different points in its length, each of said means adapted to draw a portion of the main column of air therefrom, and to discharge it into said column at points between the ends of the latter in such manner as to move the latter in a direction lengthwise of the tunnel, said blasts being in effect directed into the center of said column, and in a direction substantially parallel therewith. 70

In witness whereof, I have hereunto signed my name in the presence of two subscribing witnesses.

SAMUEL CLELAND DAVIDSON.
